PRODUCTION OF STEAM

Edward W. Butzler, West View, Pa.

Application March 9, 1942, Serial No. 433,902

10 Claims. (Cl. 122—379)

This invention relates generally to the production of steam and more particularly to a method in which one or more high pressure boilers and one or more low pressure boilers are employed and the blowdown from the high pressure boiler is supplied to the low pressure boiler. The use of the blowdown from the high pressure boiler in the low pressure boiler results in great savings in fuel and chemicals used in treating the water, as will be pointed out more particularly hereinafter.

In the accompanying drawings, which illustrate a preferred embodiment of the invention, as well as a conventional method,

Fig. 1 illustrates in a diagrammatic manner a preferred embodiment according to the present invention, in which the blowdown from a high pressure boiler is supplied to a low pressure boiler; and

Fig. 2 illustrates a conventional method in which two separate boilers are employed, one being a high pressure boiler and the other a low pressure boiler.

Referring more particularly to Fig. 1, which illustrates a preferred embodiment of the present invention, the arrangement is such as to produce 900,000 pounds per hour of steam at 900 pounds per square inch absolute pressure and 400,000 pounds per hour of steam at 240 pounds per square inch absolute pressure. Feed water, in the amount of 1,000,000 pounds per hour, which has been heated to a temperature of 220° F. by any suitable type of preheater, is supplied to a high pressure boiler 2. In the water in the high pressure boiler, a PO₄ concentration of 60 parts per million is maintained in solution, in order to inhibit the formation of adherent scale. The method of treating steam boiler water with phosphate in order to form the desired non-adherent sludge of calcium phosphate is more particularly described in Hall Patent 1,613,656, granted January 11, 1927, and reference is made thereto for further details as to the proper concentration of phosphate radical in solution to prevent the calcium from being deposited as adherent scale. The boiler water in the high pressure boiler 2

has a concentration of 2000 parts per million of total solids.

The high pressure boiler 2 is blown down continuously or from time to time into the low pressure boiler, the blowdown amounting to 10% of the water fed to the high pressure boiler or 100,000 pounds per hour. This amount of blowdown maintains the concentration of total solids in the high pressure boiler at about 2000 parts per million, thereby preventing objectionable carryover of water with the steam. The temperature of the blowdown from the high pressure boiler is about 532° F., each pound containing 529.5 B. t. u., so that the total heat in the blowdown per hour is 52.9 million B. t. u.

The blowdown from the high pressure boiler is supplied to a low pressure boiler 3, in which a PO₄ concentration of about 30 parts per million in solution and a concentration of total solids of about 4,000 parts per million are maintained. This boiler produces 400,000 pounds per hour of low pressure steam at a pressure of 240 pounds per square inch absolute. The feed water required in addition to the blowdown from the high pressure boiler, to produce the 400,000 pounds per hour of steam and provide adequate blowdown from the low pressure boiler amounts to 368,400 pounds per hour, which is supplied to the low pressure boiler at a temperature of 220° F. In order to produce the 400,000 pounds per hour of low pressure steam, it is necessary to supply 383.2 million B. t. u. per hour. It is to be noted particularly that the blowdown from the low pressure boiler 3 is regulated in such manner that the water in the low pressure boiler is more concentrated with respect to total solids than is the water in the high pressure boiler 2. In the specific method used for illustrating the invention, the concentration of total solids in the low pressure boiler is 4,000 parts per million, whereas in the high pressure boiler it is 2,000 parts per million. Furthermore, the concentration of phosphate in solution in the low pressure boiler is only 30 parts per million as compared with 60 parts per million

in the high pressure boiler. In order to operate at a total solids concentration in the low pressure boiler of 4,000 parts per million, the blowdown from the low pressure boiler amounts to 68,400 pounds per hour. Of this total blowdown, 18,400 pounds per hour is the regular blowdown (amounting to 5% of the water fed to the low pressure boiler) and 50,000 pounds per hour is the amount required to take care of the solids introduced into the low pressure boiler from the blowdown from the high pressure boiler. It will be noted that the 100,000 pounds per hour of blowdown from the high pressure boiler introduces 200 pounds per hour of solids into the low pressure boiler and that the 50,000 pounds per hour of blowdown from the low pressure boiler removes 200 pounds per hour of solids. The blowdown water from the low pressure boiler 3 is at a temperature of 397° F., so that the total heat lost by blowdown is 25.4 million B. t. u. per hour.

In the preferred method according to the present invention, the total solids in the low pressure boiler 3 are maintained higher than in the high pressure boiler 2 and the concentration of phosphate in solution in the low pressure boiler is maintained at a lower value than the concentration of phosphate in solution in the high pressure boiler. This results in a double reduction in the pounds of phosphate lost in the blowdown from the low pressure boiler. Thus the 100,000 pounds per hour of blowdown from the high pressure boiler, which has a phosphate concentration in solution of 60 parts per million, introduces 6 pounds per hour of phosphate in solution into the low pressure boiler. The 68,400 pounds per hour of blowdown from the low pressure boiler, the water in the low pressure boiler having a concentration in solution of 30 parts per million, removes 2.0 pounds of phosphate in solution per hour. Thus 4.0 pounds per hour of phosphate in solution is available for treating the feed water introduced into the low pressure boiler.

A part of the advantages of the present invention can be obtained by keeping the concentration of total solids in the low pressure boiler the same as in the high pressure boiler but maintaining a lower concentration of phosphate in solution in the low pressure boiler than in the high pressure boiler. Thus assume that the concentration of total solids in both the high pressure boiler and in the low pressure boiler is 2,000 parts per million, that there are 60 parts per million of phosphate in solution in the high pressure boiler and 30 parts per million of phosphate in solution in the low pressure boiler. The 100,000 pounds per hour of blowdown from the high pressure boiler supplied to the low pressure boiler will introduce 6 pounds of phosphate in solution into the low pressure boiler. In order to maintain the concentration of total solids in the low pressure boiler at 2,000 parts per million, it will be necessary to blow down 100,000 pounds per hour from the low pressure boiler, in order to take care of the solids in the blowdown from the high pressure boiler, and 44,400 pounds per hour to take care of the solids from the feed water supplied to the low pressure boiler or a total blowdown from the low pressure boiler of 144,400 pounds per hour. The loss in phosphate in solution is 4.3 pounds per hour, so that 1.7 pounds per hour is available for treating the feed water introduced into the low pressure boiler.

In a similar manner, a part of the advantages

of the present invention may be obtained by keeping the concentration of phosphate in solution the same in the high pressure boiler and the low pressure boiler but maintaining a higher concentration of total solids in the low pressure boiler than in the high pressure boiler. Thus assume that the phosphate concentration in solution in each boiler is 60 parts per million, that the total solids in the high pressure boiler is 2,000 parts per million and in the low pressure boiler is 4,000 parts per million. As previously explained, the blowdown from the high pressure boiler will introduce 6 pounds of phosphate in solution per hour into the low pressure boiler. Since the concentration of total solids in the low pressure boiler is increased two-fold as compared with the concentration of total solids in the high pressure boiler, it is only necessary to blow down from the low pressure boiler 50,000 pounds per hour to take care of the solids introduced into the low pressure boiler from the blowdown from the high pressure boiler. The total blowdown from the low pressure boiler is 68,400 pounds per hour, as shown in Fig. 1. The loss of phosphate in solution is 4.1 pounds per hour, so that 1.9 pounds per hour is available for treating the feed water introduced into the low pressure boiler.

Reference is now made to Fig. 2, in which the same amount of high pressure steam and the same amount of low pressure steam as are produced in accordance with the method of Fig. 1 are produced by two separate boilers according to conventional practice.

In order to produce the 900,000 pounds per hour of high pressure steam at 900 pounds per square inch absolute, 1,000,000 pounds of feed water at a temperature of 220° F. is introduced into the high pressure boiler 4. The blowdown from the boiler 4 is introduced into a flash tank 5 which produces flash steam in the amount of 19,000 pounds per hour at a pressure of 240 pounds per square inch absolute.

Where it is desired to produce the same amount of high pressure steam and low pressure steam as was produced according to the method shown in Fig. 1, it is necessary to provide a low pressure boiler which will produce 381,000 pounds of steam per hour at 240 pounds per square inch absolute pressure. This may be accomplished by the use of the separate low pressure boiler 6 shown in Fig. 2. In order to produce this amount of low pressure steam, it is necessary to feed into the boiler 6, 401,000 pounds per hour and to supply to the boiler 6, 389.2 million B. t. u. per hour. The blowdown from the boiler 6 is 5% of the feed water or 20,000 pounds per hour. The temperature of the blowdown is 397° F., so that 7.4 million B. t. u. are lost in the blowdown per hour.

The method according to the present invention, as shown in Fig. 1, results in very material savings in fuel, chemicals used in the treatment of the water in the boilers, and in the preheaters and in the amount of feed water supplied to the low pressure boiler. The saving in high level heat by the method illustrated in Fig. 1 as compared with that of Fig. 2 is shown by the following table. The computations in this table do not include the usual heat saving brought about by passing in heat exchange relation with feed water the unflashed blowdown water from the flash chamber of the high pressure boiler in the system shown

75 in Figure 2.

TABLE I
Furnace heat

	Million B. t. u./hr.
Furnace heat input L. P. boiler—Fig. 2	389.2
Furnace heat input L. P. boiler—Fig. 1	383.2
Savings furnace heat input L. P. B.	6.0

Blowdown heat

	Million B. t. u./hr.
Conventional method (Fig. 2) (30.1+7.4) million B. t. u./hr.	37.5
Proposed method (Fig. 1)	25.4
Savings	12.1

	Million B. t. u./hr.
Furnace heat saved	6.0
Blowdown heat saved	12.1
Total heat saved	18.1

	Million B. t. u./day.
Total heat saved	434.40

Assuming coal cost at bunker at \$2.50 per ton, 12,500 B. t. u./pound burned at 80% efficiency, each million B. t. u. available as steam costs:

$$\frac{1,000,000}{2000 \times 12,500 \times 0.8} \times \$2.50, \text{ or } \$0.125$$

$$434.4 \times \$0.125 = \$54.30 \text{—coal saved per day.}$$

The saving in phosphate used for treating the boiler water is illustrated by the following:

TABLE II

Phosphate lost by blowdown using conventional method (Fig. 2)

	(Blowdown from H. P. boiler #/hr.)	(Eq. wt. P_2O_5)	(p. p. m. PO_4 in H. P. boiler water)		
H. P. boiler	100,000 1,000,000	X 31.7	X 60		4.85 #/hr. P_2O_5 equivalent
		(Eq. wt. PO_4)			
L. P. boiler	20,000 1,000,000	X 31.7	X 30		.45 #/hr. P_2O_5 equivalent

Total

	<i>Phosphate lost by blowdown using proposed method (Fig. 1)</i>				
L. P. boiler	68,400 1,000,000	X 31.7	X 30		1.54 #/hr. P_2O_5 equivalent
Phosphate lost by conventional method (Fig. 2)					5.3 #/hr. P_2O_5 equivalent
Phosphate lost by proposed method (Fig. 1)					1.54 #/hr. P_2O_5 equivalent
Net Saving by proposed method (Fig. 1)					3.76 #/hr. P_2O_5 equivalent
Cost of P_2O_5 , based on current market price of disodium orthophosphate anhydrous (48% P_2O_5) at 7.25¢/#, is \$0.151 per pound					
24 $\times$ 3.76 $\times$ \$0.151 = \$10.00 per day saving on phosphate					

The savings in feed water is illustrated in Table III, this table also showing the savings in lime, soda and phosphate as P_2O_5 due to the decreased feed water requirements:

TABLE III
Feed water saved

	Pounds/hr.
Feed water used by conventional method (Fig. 2) (1,000,000+401,000)	1,401,000
Feed water used by proposed method (Fig. 1) (1,000,000+368,400)	1,368,400
Feed water saved by proposed method	32,600

Cost per million pounds feed water

Lime-soda treatment	\$2.40
Phosphate as (P_2O_5) 10# at 15.1¢/#	1.51
	\$3.91

$$24 \times 32,600 \times \$3.91 = \$3.06 \text{ per day saved.}$$

The total savings per day in fuel and chemicals is shown by Table IV. This table does not include the cost of the feed water itself before treatment with chemicals, which, if included, would further increase the savings of the pro-

posed method as compared with the method shown in Fig. 2.

TABLE IV

Total savings per day in fuel and chemicals

Coal	\$54.30
Phosphate from blowdown	10.00
Lime, soda and phosphate due to decreased feed water requirements	3.06
Total	\$67.36

or \$24,586.40 per year.

For the purpose of illustrating the method, I have given an example in which the high pressure boiler 2 operates at a pressure of 900 pounds per square inch absolute and the low pressure boiler 3 operates at a pressure of 240 pounds per square inch absolute. These pressures are merely illustrative and it will be understood that other pressures may be employed. Thus the terms "high pressure boiler" and "low pressure boiler" signify simply that the high pressure boiler operates at a pressure which is considerably higher than the pressure in the low pressure boiler.

While I have illustrated and described a preferred embodiment of the invention, it is to be understood that the invention may be otherwise embodied or practiced within the scope of the following claims.

I claim:

1. The method of producing high pressure steam and low pressure steam, which comprises producing steam in a high pressure boiler from feed water containing scale forming solids, blowing down the high pressure boiler, supplying the blowdown from the high pressure boiler to a low pressure boiler, and supplying heat to the low pressure boiler to produce low pressure steam.

2. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying heat to the low pressure boiler to produce low pressure steam while maintaining sufficient phosphate radical in solution in the boiler water to inhibit the formation of adherent scale but at

75 a phosphate concentration lower than in the high

pressure boiler water, and blowing down the low pressure boiler.

3. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying heat to the low pressure boiler to produce low pressure steam while concentrating the total solids in the water in the low pressure boiler to a higher value than the concentration of total solids in the water in the high pressure boiler, and blowing down the low pressure boiler.

4. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying heat to the low pressure boiler to produce low pressure steam while maintaining sufficient phosphate radical in solution in the boiler water to inhibit the formation of adherent scale but at a phosphate concentration lower than in the water in the high pressure boiler, concentrating the total solids in the water in the low pressure boiler to a higher value than the concentration of total solids in the water in the high pressure boiler, and blowing down the low pressure boiler.

5. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying heat to the low pressure boiler to produce low pressure steam while maintaining sufficient phosphate radical in solution in the boiler water to inhibit the formation of adherent scale but at a phosphate concentration lower than in the water in the high pressure boiler, concentrating the total solids in the water in the low pressure boiler to a higher value than the concentration of total solids in the water in the high pressure boiler, and blowing down the low pressure boiler in such manner that the blowdown from the low pressure boiler is less than the blowdown from the high pressure boiler.

6. The method of producing high pressure steam of the order of about 900 pounds per square inch absolute and low pressure steam of about 240 pounds per square inch absolute from feed water containing scale forming solids, which comprises producing steam in a high pressure boiler while maintaining a PO_4 concentration in solution of about 60 parts per million and a concentration of total solids of the order of about 2000 parts per million, blowing down the high

pressure boiler, supplying the blowdown from the high pressure boiler to a low pressure boiler, supplying heat to the low pressure boiler to produce low pressure steam while maintaining a PO_4 concentration in solution of about 30 parts per million and a concentration of total solids of the order of about 4000 parts per million, and blowing down the low pressure boiler.

7. Apparatus for producing high pressure steam and low pressure steam from feed water containing scale forming solids, which comprises a high pressure boiler, a low pressure boiler, and means connecting the high pressure and low pressure boilers for supplying blowdown from the high pressure to the low pressure boiler, and means for supplying phosphate radical to the high pressure boiler.

8. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying feed water containing scale forming solids to the low pressure boiler, supplying heat to the low pressure boiler to produce low pressure steam while concentrating the total solids in the water in the low pressure boiler to a higher value than the concentration of total solids in the water in the high pressure boiler, and blowing down the low pressure boiler.

9. The method of producing high pressure steam and low pressure steam, which comprises producing steam in a high pressure boiler from feed water containing scale forming solids while maintaining sufficient phosphate radical in solution in the boiler water to inhibit the formation of adherent scale, blowing down the high pressure boiler, supplying the blowdown from the high pressure boiler to a low pressure boiler, supplying feed water containing scale forming solids to the low pressure boiler, supplying heat to the low pressure boiler to produce low pressure steam while maintaining sufficient phosphate radical in solution in the boiler water to inhibit the formation of adherent scale but at a phosphate concentration lower than in the water in the high pressure boiler, concentrating the total solids in the water in the low pressure boiler to a higher value than the concentration of total solids in the water in the high pressure boiler, and blowing down the low pressure boiler.

10. Apparatus for producing high pressure steam and low pressure steam from feed water containing scale forming solids, which comprises a high pressure boiler, a low pressure boiler, means connecting the high pressure and low pressure boilers for supplying blowdown from the high pressure to the low pressure boiler, means for supplying feed water containing scale forming solids to the low pressure boiler, and means for supplying phosphate radical to the high pressure boiler.

EDWARD W. BUTZLER.
